FLOOR FINISHING MACHINE

Arthur N. Emmons, Nedrow, N. Y., assignor to
The Porter-Cable Machine Company, Syra-
cuse, N. Y., a Corporation of New York

Application November 3, 1928. Serial No. 318,143

3 Claims. (Cl. 51—174)

This invention relates to abrading machines, particularly portable abrading machines or surface and floor sanders, and has for its object means by which a floor board and the like can be finished close up to the end thereof with the grain 5 of the wood without having the belt come in contact with any surface at an angle to the end of the board as a mop board, wall and the like.

The invention consists in the novel features 10 and in the combinations and constructions hereinafter set forth and claimed.

In describing this invention, reference is had 15 to the accompanying drawings in which like characters designate corresponding parts in all the views.

Figure 1 is a side elevation of a machine provided with my invention.

Figure 2 is a plan view thereof, partly broken away and parts being omitted.

Figure 3 is a fragmentary elevation of a modified form of the nose or apex over which the belt runs.

Figure 4 is a fragmentary plan view of the apex member shown in Figure 1.

The abrading machine comprises generally, a suitable frame 1, front and rear rollers 2, 3 suitably mounted on the frame, an abrading belt 4 running over the rollers, means as an electric motor mounted in a housing 5 on the frame and connected to one of the rollers, as the rear roller 3 by any suitable mechanism, and means for deflecting the portion of the belt in front of the front roller to form an apex at the front of the machine, the run of the belt from the lower side 30 of the apex being in nearly a horizontal plane below a plane tangent to the lowermost portion of the front roller 2, and the portion of the belt above the apex being inclined but slightly out of a vertical plane or extending a little distance in front 35 of a plane tangent to the frontmost portion of the front roller 2.

The rear roller is supported on a suitable axle and the front roller is preferably adjustable forwardly and rearwardly to tighten the belt, the axle thereof being carried by a yoke 6 having a stem 7 slidable in an opening in a block 8 forming part of the frame, the stem being pressed in one direction by a spring 9 and having an adjusting nut 10 for moving it against the action of a spring.

The axle 11 for the front roller is carried by an angle lever 12 pivoted at its angle 13 to the yoke 6, one arm of the angle lever extending along a side member 14 of the yoke 6 and being connected thereto by suitable means, as a screw by 55 which the lever 12 can be moved on its pivot 13

to vary the angularity of the axle for the purpose of causing the belt to run straight.

This invention comprises an apex or nose 15 extending transversely of the front end of the frame in front of the front roller 2, this apex being located slightly below a plane tangent to the lowermost side of the front roller 2 and slightly in front of a plane tangent to the foremost surface of the roller 2, so that the front end of the belt 4 has an angular formation with the lower run thereof adjacent the apex 15 located in nearly a horizontal plane and the portion on the upper side of the apex inclined slightly downwardly and forwardly out of a vertical plane.

The apex or nose 15 is provided on the front end of a support 16 secured to the under side of the block 8 and spaced apart from the lower run 70 of the belt and having a plate portion 17 deflected downwardly slightly and extending under the front roller, the portion 17 constituting a pressure plate. Preferably, the pressure plate 17 is provided with a yielding portion over which the belt runs, this yielding portion being here illustrated as provided by a felt padding 18. A roller 27 of small diameter may be provided at 75 the front end portion 17 of the support 16, the roller fitting a concave channel 28 at the front edge of the support and being held from endwise movement by suitable means as notched lugs or forks 27 projecting forwardly from the bottom 80 of the channel into a circumferential groove 30 in the roller. As seen in Figure 3, the roller may be omitted and the padding 18 extended around the front end of the plate 17. In the construction shown in Figure 3, the padding is overlaid with 85 a wearing surface as a thin sheet of metal 19 which is held at its front end and connected at its rear end to means for tightening it. It is held at its front end by a strip 20 overlying the upper margin of the plate 17 and screws 21 passing through the strip 20, the underlying 90 margins of the sheet 19 and felt padding 18 and threading into the pressure plate. It is secured at its rear end to means operable to tighten it, this means being here shown as one or more 95 bolts 22 and nuts 23, the bolts 22 extending through lugs as 24 on the lower side of the rear portion of the support 16, the bolts having hooks which enter suitable holes in the rear end of the sheet 19. The bolts are tightened by means of 100 nuts 23.

The frame is provided with a suitable handle 25 and also with rollers or casters 26 at its rear end for supporting the rear end of the belt off the floor or surface so that the belt bears on 110

the surface being finished only at a point adjacent the nose or apex 15, the amount of bearing surface depending upon the adjustment of the rollers 26.

5 Owing to the apex 15 and the location thereof, a surface or a board can be finished to the end thereof with the grain of the wood without the front of the belt coming in contact with the mop board or other surface board.

10 What I claim is:

1. An abrading machine comprising a frame, front and rear rollers carried by the frame, an abrading belt running over the rollers, and means located in front of the front roller and 15 forming an apex located in front of and below the front roller, over which the belt runs from the front roller, said means being provided with a yielding pad on the lower side thereof and on the apex, over which the belt runs and a sheet metal facing overlying the padding, and means 20 for tightening the sheet metal facing.

2. An abrading machine comprising a frame, front and rear rollers carried by the frame,

an abrading belt running over the rollers, and means located in front of the front roller and forming an apex located in front of and below the front roller, over which the belt runs from the front roller, said means being provided with a yielding pad on the lower side thereof and on the apex, over which the belt runs and a sheet metal facing overlying the padding, and means for securing the sheet metal facing, and the padding at one end and means connected to the sheet at its other end for tensioning it. 80

3. An abrading machine comprising a frame, front and rear rollers carried by the frame, an abrading belt running over the rollers, and means located in front of the front roller and forming an apex located in front of and below the front roller, over which the belt runs from the front roller, said means being provided with a yielding pad on the lower side thereof and on the apex, over which the belt runs, and means for tensioning the pad. 90 95
